CRADLE ATTACHMENT FOR TELEPHONES

Jean George Mourra, 4922 SW. 87th Place, Miami, Fla.

Filed Aug. 15, 1961, Ser. No. 66,594

Term of patent 14 years

(Cl. D26—14)

FIGURES 2 and 3 are front and rear elevational views respectively, thereof;

I claim:

The ornamental design for a cradle attachment for telephones, as shown.
